UNITED STATES PATENT OFFICE.

OSCAR KATZENBERGER, OF SAN ANTONIO, TEXAS, ASSIGNOR OF ONE-HALF
TO WILLIAM W. JOHNSON, OF SAN ANTONIO, TEXAS.

LOCK.

SPECIFICATION forming part of Letters Patent No. 693,719, dated February 18, 1902.

Application filed October 11, 1901. Serial No. 78,857. (No model.)

To all whom it may concern:

Be it known that I, OSCAR KATZENBERGER, a citizen of the United States, residing at San Antonio, in the county of Bexar and State of Texas, have invented certain new and useful Improvements in Locks, of which the following is a specification.

My invention relates to improvements in keyless locks, or, more particularly, locks made on the principles covered in Letters Patent No. 678,956, granted to me on July 23, 1901.

The purpose of the invention is to so improve the said principles and parts as to permit their application to every variety of lock that is made—such, for instance, as door-locks, padlocks, mail-box locks, cabinet-locks, drawer-locks, chest-locks, elevator-locks, bicycle-locks, safe-locks, automobile-locks, and so on to all other kinds of locks where these principles can be made to apply—such improvements to consist of such an arrangement of the parts as to permit the application of the tumblers to the bolt direct instead of to the auxiliary bolt, as heretofore, and such changing of the parts as to permit the use of a concavo-convex spring to produce the necessary friction on the tumblers instead of the spiral spring, as heretofore, to permit of the use of a dog and ratchet-wheel, the latter having a smooth place for the beginning, and to communicate the combination by sound or touch instead of the means heretofore employed.

The invention consists in the novel construction and combination of the several parts, as will be hereinafter fully set forth, and pointed out in the claims.

Reference is to be made to the accompanying drawings, forming a part of this specification, in which similar characters of reference indicate corresponding parts in all the figures.

Figure 1 is a vertical section of the lock and a portion of a box and door to which it is applied. Fig. 2 is a vertical section on the longer dotted line indicated in Fig. 1. Fig. 3 is a similar section on the shorter dotted line indicated in Fig. 1. Fig. 4 is a transverse horizontal section of the lock and the box and door to which it is applied. Fig. 5 is a detail section. Fig. 6 is a sectional view of a pad-

lock to which my invention is applied. Fig. 7 is a sectional view illustrating the application of my invention to a street-letter-box lock.

In Fig. 1, A represents either the casing of the door, on which the lock is fastened, or the outside casing of the lock. B represents the knob that operates the combination. This knob culminates in a spindle which runs through from the outside of the door or lock 60 into the body of the lock and engages the tumbler C, the spring D, and the ratchet-wheel E in such a manner as when the knob B is turned C, D, and E turn with it, except when the tumbler C is held stationary. Then 65 if the knob and its corresponding axle or spindle are turned the position of such tumbler C on such axle will be changed. In this manner the changing of the combination is effected, as is hereinafter more fully set forth. 70 The tumbler C, shaped substantially as shown in Fig. 1, made solid of metal or other suitable substance, is provided with a flat edge, as shown, of such depth as to raise the bolt or auxiliary bolt the required height. This 75 tumbler is circular in form, except the shoulder F, as shown, which is of such diameter and thickness as required. The edge of the saucer shaped spring-washer D rests upon that face of the tumbler C which is circular and 80 near the edge of such face, whereby a maximum extent of bearing-surface and a corresponding degree of friction are provided for. The tumblers are mounted loosely, and hence rotatably, on the spindles F. The concavo- 85 convex springs D are secured by a nut or collar on spindles F, so as to apply due pressure and friction on the tumblers C, so that in the ordinary turning of the knob and its axle the tumbler, spring, and ratchet will all turn together without slipping, while at the same time when the tumbler is held firmly the knob, axle, and ratchet may be turned, leaving the tumbler stationary, thus changing the combination. The ratchet E in Fig. 1 is provided with teeth and a smooth place by which to locate the beginning of the combination or rotation by sound or touch, or both. The ratchet has a square hole in the center, substantially as shown in Figs. 2 and 3. The 90 dogs H H in Figs. 2 and 3 are pivoted at I I and are held in position by the springs J J,

fastened at K K. These dogs and their corresponding teeth on the ratchet-wheels are so shaped that when the wheel is on the axle in the position as shown in Fig. 2 the knob B 5 can be turned only to the right, while if it is reversed and placed on the axle as shown in Fig. 3 the said knob may be turned in either direction—that is, either to the right or to the left.

- 10 Figs. 1, 2, 3, and 4 show the application of the principles of this lock to a lock for post-office boxes and other similar locks. L represents the bolt, pivoted at M. The tumblers C C C work directly against the main bolt.
- 15 When the bolt is in position as shown in Fig. 4, the door is locked, the end of the bolt being behind the projection N on the frame of the door Q. When the tumblers C C C are all turned flat side up, the bolt L will fall 20 down to the opening O, (see Fig. 3,) and thus allow the door to open. The door may be opened from the inside without lining up the tumblers by lifting the end of the bolt L up to the opening provided for the purpose, and 25 the door may be closed in like manner by lifting the bolt through the opening before referred to. This last operation is facilitated by giving a slight slope to the projection N from the outside. The projection N is also 30 sloped slightly from the inside to minimize the chances of changing the combination accidentally while closing the door.

Fig. 5 represents the principles applied to a padlock. The tumblers C C C C operate 35 against the bolt R, which is pivoted in the center, as shown. The spring T throws the neck S open as soon as the tumblers C C C C are lined up, and the spring U throws the bolt back, disengaging the bolt from the neck, 40 substantially as shown.

Fig. 7 shows the application of the principles to a street-letter-box lock and other locks of similar construction. The tumblers C C C operate directly against the bolt V, substantially as shown.

45 Figs. 1, 2, and 4 show the operation of the spring W, fastened to the back of the door Q in such manner as to operate against the jamb of the door and throw it open as soon as unlocked and to keep it open until the combination is thrown.

The operation of the lock is substantially the same as described in my former patent, No. 678,956, the notches in the ratchet-wheels 55 taking the place of the depressions and the dog the place of the pointed spring.

Having thus described my invention, I

claim as new and desire to secure by Letters Patent—

1. In a lock of the character described, the 60 combination, with a pivoted bolt, of a circular tumbler having a portion of one face cutaway or flattened, the edge being left circular, a concavo-convex spring applied to such tumbler, a tumbler-spindle having a knob, and 65 means for locking the tumbler, substantially as shown and described.

2. In a lock of the character described, a tumbler, which is circular in form, having a portion of one face cut away, the edge being 70 left intact, as shown and described.

3. In a lock of the character described, a ratchet-wheel having a smooth place for the beginning of the combination, a dog to operate against such ratchet-wheel and a spring 75 to hold such dog in position; the teeth on such ratchet-wheel and the dog being so shaped as to enable the said wheel to be turned either to the right or to the left; and means of fastening such ratchet-wheel onto the axle carrying the tumbler; the purpose of such ratchet-wheel, dog, &c., being to communicate the combination either by hearing or by touch, substantially as set forth.

4. In a lock of the character described, the 85 combination, with the casing, and pivoted bolt, of a tumbler, which is circular and has a portion of one face cut away, a concavo-convex spring bearing upon the tumbler, a spindle whereon the tumbler and spring are 90 mounted rotatably, a ratchet-wheel fixed on the spindle and having a portion of its periphery smooth, and a pivoted dog which engages such wheel, all arranged and operating as shown and described.

95 5. In a lock of the character described, the combination, with casing, pivoted bolt-spindle, a circular tumbler cut away on one face, a spring acting on the tumbler and a ratchet-wheel fixed on the spindle and having one 100 side flattened, of a pivoted spring-pushed dog having a V-shaped head adapted to engage the ratchet and thus permit the latter to be rotated in either direction, whereby the combination is communicated either by touch 105 or hearing, as specified.

In testimony whereof I have signed my name to this specification in the presence of two subscribing witnesses.

OSCAR KATZENBERGER.
